CHAIN GUARD

Albert J. Cich, Buffalo, N. Y., assignor to Elrae
Pressed Metals, Inc., Buffalo, N. Y., a corpora-
tion of New York

Application February 20, 1948, Serial No. 9,690

1 Claim. (Cl. 74—611)

1 This invention relates to a chain guard and more particularly to a bracket whereby the guard shield of the chain guard of the driving mechanism of a cycle is mounted on a bar of the cycle frame or the like.

The means which have been employed heretofore for this purpose comprise an undue number of parts which involved unnecessary expense and the same were also of such character that it was difficult to handle the parts of the guard frame for connecting the same with the cycle frame bar.

It is the object of this invention to provide a bracket for this purpose which comprises a minimum number of parts, that can be produced at low cost and which can be easily and conveniently handled while applying the same to the guard and cycle frame bar.

In the accompanying drawings:

Fig. 1 is a fragmentary inner side view of a cycle frame bar and a guard for the chain of a driving mechanism which are adapted to be connected by the bracket embodying this invention, and showing the frame bar arranged at an angle to the horizon.

Fig. 2 is an outer side view of the same, but showing the frame bar in a horizontal position.

Fig. 3 is a cross section taken on line 3—3, Fig. 2.

Fig. 4 is a longitudinal section on an enlarged scale, taken on line 4—4, Fig. 3.

Fig. 5 is a transverse section taken on the correspondingly numbered line in Fig. 4.

In the following description the same reference number is applied to the same part in the several views of the drawings.

The numeral 10 represents a bar of the cycle frame upon which is mounted the guard shield 11 which protects the clothing of the rider from the chain of the driving mechanism of the cycle, as in a pedal propelled bicycle. This bar is usually round in cross section and of tubular form and is arranged in various positions in different makes of bicycles, the same being shown in an inclined position in Fig. 1, and in a horizontal position in Figs. 2 and 4.

The guard shield 11 is usually constructed of sheet metal and in various shapes to conform to the driving mechanism with which it is associated, that shown in Figs. 1, 2 and 3 comprising a vertical wall having an upper part 12 which is arranged lengthwise of the cycle and substantially horizontal and a front part 13 which curves downwardly from the front end of the upper part, and a flange projecting laterally

from the vertical wall and having an upper straight part 14 arranged on the upper edge of the longitudinal part of the guard wall and a front curved part 15 which is arranged on the curved edge of the front part of this wall.

The bracket which embodies this invention is adjustable so as to permit of mounting guard shields on frame bars which are arranged in different relative positions and in the preferred form of this bracket the same is constructed as follows:

The numerals 16 and 17 represent front and rear vertical hinge ears which are arranged side by side in an overlapping relation lengthwise of the frame bar and guard and are pivotally connected by a horizontal rivet 18 passing transversely through the same so that these ears can be turned vertically relative to one another for adapting the bracket to guards and frame rods which may be arranged in different relative positions.

The front hinge ear 16 is provided at its front end with a curved attaching flange 19 which projects laterally therefrom and is secured to the inner side of the curved part 15 of the guard flange by bolts 20 passing through the flange 15 and through longitudinal slots 21 in the ear flange 19 whereby the respective hinge ear may be adjusted angularly on the guard to suit different conditions. The front hinge ear and its flange may be economically made from a single piece of sheet metal.

The rear hinge ear 17 is detachably and adjustably connected with the frame bar 10 by a clamping device which embodies this invention and is preferably constructed as follows:

This clamping device comprises two clips, one of which has a semi-cylindrical clamping jaw 22 connected with the rear end of the rear hinge ear 17 and adapted to engage one side of the frame bar and the other clip having a cylindrical clamping jaw 23 which is adapted to engage with the opposite side of the frame bar and is detachably connected with the jaw 22. The last mentioned jaw is formed integrally with the rear hinge ear 17 of the sheet metal.

The preferred means for detachably connecting the two clamping jaws shown in the drawings include an eye 24 projecting outwardly from one end of the clamping jaw 23, an outwardly projecting lip 25 arranged on the corresponding end of the other jaw 22 and extending through said eye, two fastening lugs 26 projecting laterally from the other corresponding ends of said jaws, and a clamping screw 27 connecting said lugs, as best

shown in Figs. 3 and 5. By these means the bracket can be quickly connected with the frame bar and also adjusted lengthwise thereon for properly fitting the guard to the chain of the bicycle operating mechanism.

It will be noted that the axis of the rivet 18 which pivotally connects the hinge ears 16, 17 is arranged at right angles or transversely to the longitudinal axis of the cylindrical jaws of the clamping device, thereby producing a very compact structure and still permitting the same to be readily attached to the guard and frame and adjusted into the required position to suit these parts.

Owing to the reduction in the number of parts which comprise this bracket the cost of the same is materially reduced and the same can be handled more conveniently than those heretofore employed for this purpose.

I claim:

A chain guard for the drive chain of a cycle having a frame bar adjacent said chain, comprising a sheet metal guard having a curved part adopted to cover a part of said chain, a pair of semicircular sheet metal jaws engageable with opposite sides of said frame bar, means securing said jaws together and in clamping relation with said frame bar, an integral L-shaped ear extending from the curved edge of one of said jaws and projecting radially outwardly from and thence axially parallel with said frame bar, a sec-

ond sheet metal ear arranged in face-to-face relation with said first ear, a rivet pivotally connecting said ears and arranged crosswise of said frame bar, a curved sheet metal attaching flange integral with and projecting from one edge of said second ear and fitting against the inner face of said curved part of said guard, said attaching flange being elongated in the direction of its curvature and provided at its opposite ends with slots elongated lengthwise of its curvature, and bolts extending through said slots and said curved part of said guard.
